UNITED STATES PATENT OFFICE

JULIUS WEINBERGER AND IRVING WOLFF, OF NEW YORK, N. Y., ASSIGNEES TO RADIO CORPORATION OF AMERICA, A CORPORATION OF DELAWARE

LOUD SPEAKER

Original application filed March 31, 1927, Serial No. 179,743. Divided and this application filed April 24, 1930. Serial No. 446,838.

This application is a division of our application filed March 31st, 1927, Serial No. 179,743, now Patent No. 1,760,862.

This invention relates to the art of sound reproducing devices and deals more specifically with the provision of a loudspeaker device built-in or enclosed by the cabinet of a radio receiving set or phonograph.

In the usual structure of the cabinets employed in connection with radio receiving apparatus the rear wall of the cabinet is left open to provide for ventilation of certain of the radio apparatus. It, therefore, follows that when a loudspeaker device is mounted in such a cabinet the cabinet acts as a resonator, thus destroying the fidelity of response of the loudspeaker, by over-emphasizing certain of the frequencies corresponding to the natural period of the system at resonance. This effect has been explained in the following way:

The space contained within the cabinet rearwardly of the loudspeaker is a pressure area, while the mouth of the opening at the rear of the cabinet is a high velocity area. This phenomenon may be better understood from the mechanical analogy in which the air within the cabinet rearwardly of the loudspeaker may be considered a spring, while the air at the rear opening of the cabinet may be considered a mass which loads the spring and causes the vibration. The vibrations, of course are originally set up by the movement of the loudspeaker device and when the frequencies emitted from the loudspeaker approximate the frequency corresponding to the natural period of the air cavities the system resonates freely.

There are two possible ways of overcoming this undesirable effect. The first one is to stop the motion of the air behind the loudspeaker by means of an enclosure or casing. The second method is to release the pressure of air within the cabinet, or in other words to cut off the spring referred to in the above mechanical analogy by providing openings in the front of the cabinet adjacent to the loudspeaker. Either one of these methods or both in combination have been found to give highly improved results.

It is, therefore, an object of this invention

to provide a built-in loudspeaker device which will give natural and reliable characteristics of sound reproduction.

It is a further object of this invention to prevent the phenomenon or resonance in a cabinet of a built-in loudspeaker.

It is a further object of this invention to provide a loudspeaker construction adapted to give maximum acoustic efficiency of the sound reproducing diaphragm.

Further it is an object of this invention to provide a built-in loudspeaker in which the range of audible frequencies reproduced is a maximum.

These and other objects of the invention will be apparent to one skilled in the art from the following description taken in connection with the accompanying drawings in which:

Figure 1 is a front elevational view of a loudspeaker embodying this invention.

Figure 2 is a side elevational view of the device shown in Figure 1.

Figure 3 is a detailed view of a modified form of casing.

Figure 4 is a fragmentary elevation showing the loudspeaker device mounted within the cabinet.

Referring in detail to the drawings the loudspeaker is seen to comprise a vibratile diaphragm 11 to which is coupled a rod 12 which serves to connect the diaphragm to a driving unit 13 of any well known type. For the purposes of the present disclosure a cone diaphragm has been illustrated as the vibratile member but it is to be understood that the invention does not relate specifically to this type of diaphragm, but rather may be applied to any and all types of vibratile diaphragms now known, such as a flat disk, a circular vibrating member, as well as oval and other shaped cones, in fact, to any loudspeaker which radiates to the rear as well as the front. Also the particular form of driving unit forms no part of the present invention and needs no further description here. Any of the well known types of reproducing units may be employed.

Attached to the driving unit 13 are the stays or supports 14 which form a frame in the shape of a truncated rectangular pyra-

mid. Of course, other shapes may be conveniently formed but the present has been chosen as a simple and convenient means of support for the cone and driving unit.

- 5 Joined to the supports 14 is the plate 15 provided with an aperture 16, shaped to conform to the base of the vibratile member 11. The edge of the cone 11 is joined circumferentially to the plate 15 in any suitable manner.
- 10 nearer designed to provide a so-called free or floating edge. This may be accomplished, for example, by means of a strip 17 of flexible material such as a sheep-skin or any suitable textile, the strip being in the form of an annular ring shaped to overlap the edge of the cone and the edge forming the aperture 16. The inner circumference of the annular strip 17 is attached to the edge of the cone; while the outer circumference is joined to the plate 15.
- 15 20 Obviously other methods of mounting the vibrating element may be employed without departing from the spirit of this invention.

In order to overcome the undesirable effects described above resulting from the fact that the cabinet acts as a resonator, a casing 18 shaped somewhat similarly to the support 14 is provided and arranged with its upper base in a plane between the rear of the vibratile element 11 and the adjacent side of the reproducing unit. The side portions and the front edge of the casing 18 are spaced from the support 14 and also from the front face of the cone as shown in Figure 2. The casing may be made of any convenient material such as fibre board, molded compositions, wood or metal or felt. A layer of sound absorbent or cushioning material such as felt or other fibrous materials may be placed upon the inside of the reflector. The specific design of the reflector 18 may be varied widely to obtain the most satisfactory results, depending upon the particular loudspeaker device used therewith.

45 Openings 21 are provided in the front mounting plate 15 for the purpose of releasing the spring action of the vibrating air between the diaphragm 11 and the casing 18.

Referring in particular now to Figure 4, the loudspeaker device and casing are shown mounted in a cabinet 25 of any suitable radio set which may be and ordinarily is open at the rear. The assembled loudspeaker and casing are mounted within the cabinet and secured thereto in any convenient manner such as, for example, by the support 26 which may be screwed or otherwise attached to the casing and to the base of the cabinet. The abutment 27 which is joined to the cabinet cooperates with the adjacent portion of the reflector to hold the same firmly in place. The usual covering or grille 28 may be provided in front of the loudspeaker device.

60 While the modification shown in Figure 4 includes the reflector member 14 it is to be understood that under certain conditions it

may be found desirable to eliminate the use of the casing 14 and rely upon the openings 21 in the front mounting to eliminate the undesirable resonance effect. Also, while the casing has been disclosed specifically mounted between the vibrating diaphragm and the driving unit, it is to be understood that this casing may be mounted rearwardly of the said unit in accordance with the principles of this invention.

70 Referring to Figure 3 there is shown a modified form of reflector which is similar to that shown in the preceding figures but which is provided with a packing of felt or other sound absorbent material, which packing is of a thickness to practically fill the entire space between the rear of the vibrating diaphragm and the adjacent faces of the reflector member. The packing material 19 shown in this figure may be held in place in any suitable manner, such as for example, by threads or wires passing therethrough and joined to the casing. The space 24 between the packing 19 and the cone 11 has a thickness of the order of magnitude of one to two inches.

75 80 85 90 95 Claims:

1. A loudspeaker comprising a conical diaphragm, a member provided with an opening conforming to the periphery of said diaphragm, means providing a flexible connection between the periphery of said diaphragm and said member, a casing engaging said member and extending rearwardly therefrom, said casing having the shape of a frustum, and a driving unit for said diaphragm located outside of said frustum.

100 105 110 115 120 125 2. An acoustic device comprising a vibratile diaphragm, a supporting member for said diaphragm, flexible means connecting the periphery of said diaphragm with said supporting member, a casing having the shape of a frustum positioned to engage said supporting member substantially at its larger base and extending rearwardly therefrom to enclose the rear of said diaphragm, and sound absorbing material disposed within said casing to occupy substantially all of the space between the back of said diaphragm and said casing.

3. An acoustic device comprising a vibratile diaphragm, a supporting member for said diaphragm, flexible means connecting the periphery of said diaphragm with said supporting member, a casing having the shape of a frustum positioned to engage said supporting member substantially at its larger base and extending rearwardly therefrom to enclose the rear of said diaphragm, a mass of sound absorbing material disposed within said casing to occupy substantially all of the space between the back of said diaphragm and said casing, a driving unit for said diaphragm positioned outside of said casing, and members connecting said driving unit

and said supporting member, said members extending through said casing and said mass of sound absorbing material.

4. A loudspeaker comprising a conical diaphragm, a member provided with an opening commensurate with the peripheral dimensions of said diaphragm, means providing a flexible connection between said diaphragm and said member, a casing substantially engaging said member and extending rearwardly therefrom, said casing having the shape of a frustum, and driving means for said diaphragm, said frustum shaped casing being arranged so that its smaller base is interposed between said diaphragm and said driving means.

5. A loudspeaker comprising a conical diaphragm, a member provided with an opening slightly larger than the periphery of said diaphragm, flexible means connected between the periphery of said diaphragm and said member, a frustum shaped casing substantially engaging said member and extending rearwardly therefrom, said frustum shaped casing having a smaller base provided with an opening therethrough, and a driving member connected to said diaphragm and extending through the opening in said base.

6. A loudspeaker comprising a vibratile diaphragm, a supporting member, means providing a flexible connection between the periphery of said diaphragm and said supporting member, a casing substantially engaging said supporting member and extending rearwardly therefrom, said casing having the shape of a frustum, a driving unit operatively connected with said diaphragm and positioned outside of said casing, said frustum shaped casing being arranged so that its smaller base is interposed between said diaphragm and said driving unit, and sound absorbing material disposed within said casing.

7. A loudspeaker comprising a conical diaphragm, a member provided with an opening conforming to the periphery of said diaphragm, means providing a flexible connection between the periphery of said diaphragm and said member, a casing substantially engaging said member and extending rearwardly therefrom, said casing having the shape of a frustum, means for maintaining said diaphragm in fixed relation to said member, and a driving member connected to said diaphragm, said frustum shaped casing being provided with a smaller base having an opening therein through which said driving member is adapted to extend.

8. A loudspeaker comprising a conical diaphragm, a supporting member, means providing a flexible connection between the periphery of said diaphragm and said supporting member, a casing substantially engaging said supporting member and extending rearwardly therefrom, said casing having the

shape of a frustum, a driving unit for said diaphragm, said driving unit being located outside of said frustum, and means for rigidly connecting said driving unit with said supporting member.

9. A loudspeaker comprising a conical diaphragm, a supporting member, means providing a flexible connection between the periphery of said diaphragm and said supporting member, a casing substantially engaging said supporting member and extending rearwardly therefrom, a driving unit for said diaphragm, said casing having the shape of a frustum the smaller base of which is interposed between said diaphragm and said driving unit, and means separate from said casing for rigidly connecting said driving unit with said supporting member.

10. The combination of a casing for a loudspeaker having a conical diaphragm and a driving member attached thereto, with means for preventing free circulation of sound waves from the rear of the diaphragm to the front of said diaphragm, said casing comprising a frustum shaped member open at its larger base and substantially closed at its smaller base, said smaller base being provided with openings through one of which said driving member is adapted to extend, said frustum shaped member being imperforate except for said openings in its smaller base.

JULIUS WEINBERGER.
IRVING WOLFF.
